(57) **CLAIM**

The ornamental design for a table, as shown and described.

DESCRIPTION

FIG. 1 is an upper, front, and left side perspective view of a table showing my new design;

FIG. 2 is an upper, rear, and left side perspective view thereof;

FIG. 3 is an upper and left side perspective view thereof;

FIG. 4 is a front elevational view thereof;

FIG. 5 is a top plan view thereof;

FIG. 6 is a bottom plan view thereof; and,

FIG. 7 is a left side elevational view, the right side elevational view being a mirror image thereof.

The dashed lines shown in the drawings are included for purposes of illustrating environmental structure. The dashed lines and structure they depict form no part of the claimed design.
